(57) **CLAIM**

The ornamental design for a twisting wind catcher, as shown and described.

DESCRIPTION

FIG. 1 is a front elevational view of a twisting wind catcher showing my new design, the rear elevational view being the same as the front elevational view;

FIG. 2 is a left side elevational view of the wind catcher shown in FIG. 1, the right side elevational view being the same as the left side elevational view; and,

FIG. 3 is a top plan view thereof, the bottom plan view being a mirror image.
